(57) **CLAIM**

The ornamental design for the outlet portion of an electrical power cord, as shown and described.

DESCRIPTION

FIG. 1 is a perspective view for the outlet portion of an electrical power cord showing my new design, in which all three socket units are closed from being plugged in; FIG. 2 is a perspective view for the outlet portion of an electrical power cord showing my new design, in which the rear socket unit is opened for being plugged in;

FIG. 3 is a right side view thereof, the left side view being a mirror image;

FIG. 4 is a top plan view thereof;

FIG. 5 is a rear view thereof;

FIG. 6 is a bottom plan view thereof; and,

FIG. 7 is a front view thereof.

The broken lines in FIGS. 1 and 2 are included for the purpose of illustrating environmental structure only and form no part of the claimed design.
